TROMBONE

Antonio Adriani, New York, N. Y.

Application January 13, 1936, Serial No. 58,850

2 Claims. (Cl. 84—395)

This invention relates to tenor trombones or wind instruments of the trumpet variety whose tones are produced by means of a slide mechanism along cylindrical brass tubes.

5 The tenor trombones in use today have many disadvantages; the note Eb cannot be obtained without a separate attachment; the tones are most difficult to control below the fifth position due to the extension of the slide and the stretched 10 position of the arm. Because of the distance between each position, legato and staccato attacks are extremely difficult and tiring to perform. The length of the instrument while being played makes the arrangement of the orchestra an arduous 15 one and also prohibits the emission of sounds toward the audience as the slide must be directed toward the floor to save space, this in turn does not permit reading of the score without strain. The continual extended stretching of the arm to 20 the lengths required by the conventional tenor trombone tires the performer, does not permit him to relax, so that he cannot play at his best.

It is an object of this invention to provide a tenor trombone which obviates the aforementioned shortcomings.

It is an object of this invention to provide a short-positioned tenor trombone possessing a complete chromatic scale in the tenor compass and which has in addition thereto a note a semi-tone lower than that possessed in the conventional tenor trombone, namely, Eb.

It is another object of this invention to provide a tenor trombone whose weight is so evenly distributed that it will be easily balanced, permitting relaxation of the performer and whose tone and length of tubing is the same as in the conventional trombone.

It is still another object of this invention to provide a compact tenor trombone which is so constructed as to allow the performer easy control so that he can play any tempo, nuance, tone, etc., with complete ease and without any strain whatsoever.

45 These several advantageous objects are attained by the novel design, construction and arrangement of parts, as hereinafter described and illustrated in the accompanying drawing, constituting a feature of this disclosure, and in which:

50 Fig. 1 is a perspective view of a tenor trombone embodying my invention.

Fig. 2 is a view of the guide and slide portions of the device shown in Fig. 1.

55 Fig. 3 is a view showing the guide and slide portions in a modified form.

In the drawing:

The numeral 5 indicates generally the substantially U-shaped bell portion and the numeral 6 indicates generally the pipe portions. The portion 5 comprises the tubular arms 8 and 9 joined by the elbow or crook 10 and spanned by the cross pieces 11.

The pipe portion 6 comprises generally the tubular guide portion 12 and the tubular slide portion 13. The guide portion is made up of 10 the parts 14, 15, 16, and 17. The outer guide parts 17 and 14 are joined together by a cross-member 18 to provide a substantially U-shaped member or element and the inner guide parts 15, 16 are connected together by the elbow or crook 19, to provide another substantially U-shaped member element but less in width than the former U-shaped member enabling it to be located between the arms 14, 17 of the latter. The inner U-shaped member is connected to the cross-piece 18 of the outer U-shaped member by the part 20.

The slide portion 13 comprises generally the slide tubes 14a, 15a, 16a, 17a, the parts 14a and 15a being integrally connected by the tubular 25 crook or elbow 21 to provide a substantially U-shaped element or member and the slide parts 16a and 17a are also integrally connected by the tubular elbow or crook 22 providing another substantially U-shaped element or member, thus 30 producing a continuous path through, 17a, 17, 16a, 16, 15a, 15, 14a, 14, and through the bell portion 5 comprising the tubes 9, 10, 8, and 7, respectively, to produce the required sound. It is 35 to be noted that the slide parts are disposed with respect to each other such that their U ends are adjacent.

The slide parts 14a and 15a, 15a and 16a, of the slide portion 6 are held in respective spaced relation indicated by the numerals 25, 26, by the 40 spans or cross-members 24 to allow the manipulation of the slide portion to produce the various tones.

A mouthpiece 27 is connected to the free end of 45 the slide part 17a.

In Figure 2 the dotted lines indicated as 1st, 2nd, 3rd, 4th, 5th, 6th, 7th, and 8th represent the various positions of the slide for different tones which positions it is to be noted are very much shorter than in the conventional tenor trombone. The dotted line indicated by the word Bell shows the fixed position of the bell with respect to the instrument.

In Figure 3 which shows the invention in a modified form, the prime numerals represent 55

parts corresponding to the respective numerals in Figures 1 and 2 and the double prime numerals to that of the numerals shown with the letter *a*. In this figure the slide parts 14', 15' and 16', 17' are brought closer together leaving a wider space 25' in the center.

In Figure 1 the guide portion 12 is in the same plane with the slide portion 13. In Figure 3 the crooks 21', 22' of the slide portions 13' overlap.

10 It is believed from the above description that those skilled in the art will have no difficulty in understanding the construction, the method of use and operation of the device herein disclosed and a detailed discussion thereof is unnecessary.

15 The invention is of simple and practical construction and is adapted to accomplish among others all of the objects and advantages herein set forth.

Having thus described my invention, what I 20 claim as new and desire to secure by Letters Patent, is:—

1. A short-positioned trombone comprising a substantially U-shaped bell portion, and tubular guide and slide portions, said guide portion comprising four tubular spaced-apart arms, the two inner arms of which being connected by a U-shaped tubular element and the two outer arms being connected by a tubular cross-member, the 25 said element being connected to said cross-member to provide a unit, one of the outer arms of

said unit being connected to an arm of said bell portion, a mouthpiece connected to the other outer arm of said unit, said slide portion comprising two substantially U-shaped tubular parts, a cross-member joining an arm of each part, the arms of said parts adapted to slidably receive the respective arms of said guide portion, the combined relation of the portions being such as to provide a complete chromatic scale in the tenor compass and whereby the note E_b may be 10 obtained.

2. A short-positioned trombone comprising a substantially U-shaped bell member, and interlocking tubular guide and slide portions, said guide portion comprising two connected substantially 15 U-shaped parts, first and second, respectively, the second part being located between the arms of the first part, an arm of the first part being connected to said member, a mouthpiece connected to the other arm of said first part, said slide portion, comprising two substantially U-shaped tubular sections, means joining said sections together with their U ends adjacent, the arms of said slide portion adapted to slidably receive the respective arms of said guide portion, 20 the combined relation of the portions and member being such as to provide the complete chromatic scale in the tenor compass and whereby the note E_b may be obtained.

ANTONIO ADRIANI. 30
